UNITED STATES PATENT OFFICE.

M. B. STAFFORD, OF NEW YORK, N. Y.

IMPROVEMENT IN WINDOW-SASH FASTENINGS.

Specification forming part of Letters Patent No. 37,528, dated January 27, 1863.

To all whom it may concern:

Be it known that I, M. B. STAFFORD, of the city, county, and State of New York, have invented a new and Improved Widow-Sash Fastening; and I do hereby declare that the following is a full, clear, and exact description of the same, reference being had to the accompanying drawings, making a part of this specification, in which—

Figure 1 is a plan or top view of my invention in a locked state; Fig. 2, a plan or top view of the same in an unlocked state; Fig. 3, a side view of the same.

Similar letters of reference indicate corresponding parts in the several figures.

This invention relates to an improvement in that class of widow-sash fastenings which are designed for keeping the upper and lower sashes in a locked state when closed; and it consists in a novel attachment constructed and arranged in such a manner with a fastening that when the latter is moved or adjusted so as to fasten the sashes the attachment will become engaged or so adjust itself as to form a lock, and effectually prevent the fastening being operated upon from the outer side of the window.

To enable those skilled in the art to fully understand and construct my invention, I will proceed to describe it.

A represents a metal plate or bearing, which is of right-angular form in its transverse section, and is attached by screws to the center of the lower rail, a^x , of the upper sash of the window.

B is a horizontal bar, which is secured by a vertical pin or pivot, a , to the plate A. This pin, or pivot a passes through a horizontal plate, b , which is at the central part of the plate A, and is parallel with the lower part of the latter, as shown in Fig. 3. The bar B is allowed to turn freely on the pin or pivot a , and it has a notch or recess, c , made in its under side, which is also shown in Fig. 3.

To the outer end of the bar B there is attached, by a pivot or joint, d , a short bar, C, which is allowed to work or move freely up and down on said pivot or joint.

D is a metal plate, which is attached to the center of the upper cross-rail, e , of the lower sash of the window. This plate D has a ledge, f , at its outer end. The front or outer edge of this ledge is curved so as to form a segment or part of a circle of which the pin or pivot a is the center. The upper surface of the ledge

f is also inclined or curved from its center downward in each direction, so as to form curved inclined surfaces g , and at the center of said ledge there is a vertical slot, h , of sufficient width to receive the lower part of the bar C. (See Fig. 2.)

On the back part of the plate D there is a ledge, i , the front edge of which is curved, forming a segment or part of a circle the center of which is the pin or pivot a . The front side of the notch or recess c is also curved to correspond with the curvature of the front edge of the ledge i .

When the two sashes are not secured or locked in a closed state by the invention, the bar B is turned round so as to have a longitudinal position on the plate A, as shown in Fig. 2, and in order to secure the sashes in a closed state the bar B is moved around at right angles to the plate A, and during this movement of bar B the short bar C passes up one of the inclined surfaces g of the plate D, and when said bar reaches the slot h the former by its own gravity drops into said slot and forms a lock, which effectually prevents the bar B being turned off from the ledge f from the outer side of the window by the insertion of a knife-blade or a thin strip of metal between the adjoining cross-rails d e of the two sashes. This is the mode practiced by burglars in opening the old fastenings of this kind.

When the bar B is turned over the plate D, the two cross-rails a^x e are drawn together in close contact, so as to form a weather-proof joint, in consequence of the ledge i fitting in the notch or recess c in the under side of bar B.

In order to unlock the bar B, the short bar C is first raised out of the slot h , and the bar B turned either to the right or left over the plate A.

Having thus described my invention, what I claim as new, and desire to secure by Letters Patent, is—

The pivoted bar B, provided with the notch or recess c , and having the bar C attached by a joint, d , in combination with the plate D, provided with the ledge f , having inclined or curved surfaces g and the slot h , and also provided with the curved ledge i ; all arranged as and for the purpose herein set forth.

M. B. STAFFORD.
